(57) **CLAIM**

The ornamental design for a light therapy device, as shown and described.

DESCRIPTION

FIG. 1 illustrates a front perspective view of a light therapy device;

FIG. 2 illustrates a front view of the light therapy device thereof;

FIG. 3 illustrates a back view of the light therapy device thereof;

FIG. 4 illustrates a left side view of the light therapy device thereof;

FIG. 5 illustrates a right side view of the light therapy device thereof;

FIG. 6 illustrates a top view of the light therapy device thereof;

FIG. 7 illustrates a bottom view of the light therapy device thereof; and,

FIG. 8 illustrates a back perspective view of the light therapy device thereof.

The broken lines shown in the drawings are included for illustration purpose only and form no part of the claimed design.
